Primary Examiner — Cynthia Ramirez*Assistant Examiner* — Xavier Marti-Santos(74) *Attorney, Agent, or Firm* — Levenfeld Pearlstein, LLC(57) **CLAIM**

The ornamental design for a privacy chair, as shown and described.

DESCRIPTION

FIG. 1 is a top, front, right-hand side perspective view of a privacy chair showing my new design;

FIG. 2 is a front view thereof;

FIG. 3 is a rear view thereof;

FIG. 4 is a side view thereof as seen from the right-hand side of FIG. 2;

FIG. 5 is a side view thereof as seen from the left-hand side of FIG. 2;

FIG. 6 is a top view thereof;

FIG. 7 is a bottom view thereof; and,

FIG. 8 is a top, rear, left-hand side perspective view.

The broken lines in the figures are for the purpose of illustrating portions of the PRIVACY CHAIR, which form no part of the claimed design.
